US0D1112136S

(12) **United States Design Patent** (10) **Patent No.:** **US D1,112,136 S**
(45) **Date of Patent:** **** Feb. 10, 2026**

(54) **COMMUNICATION BADGE**

(71) Applicant: **Hill-Rom Services, Inc.**, Batesville, IN (US)

(72) Inventors: **Frederick Collin Davidson**, Apex, NC (US); **Richard E. Sumner**, Wake Forest, NC (US); **Brandon M. Ayers**, Carrboro, NC (US); **Theophile Reginald Lerebours**, Cary, NC (US); **Amilcar Moises Ubiera**, Cary, NC (US); **Mark F. Hettig**, Denver, CO (US); **Jennifer A. Gunn**, Durham, NC (US)

(73) Assignee: **Hill-Rom Services, Inc.**, Batesville, IN (US)

(**) Term: **15 Years**

(21) Appl. No.: **29/936,732**

(22) Filed: **Apr. 10, 2024**

(51) LOC (15) Cl. **14-02**

(52) U.S. Cl.

USPC **D14/137**

(58) **Field of Classification Search**

USPC ..... D14/137, 138 AA, 147, 155, 159, 172, D14/188, 191, 192, 194-198, 203.1, D14/203.3, 203.5, 203.7, 214, 219, 221, D14/226; D21/517, 566, 324, 329, 331; D13/168; D30/199

CPC H04M 1/233; G08B 21/0202

CLAIM

The ornamental design for a communication badge, as shown and described.

DESCRIPTION

FIG. 1 is a first isometric view of a communication badge in accordance with our design;

FIG. 2 is a second isometric view of the communication badge in accordance with our design;

FIG. 3 is a front view of the communication badge in accordance with our design;

FIG. 4 is a top view of the communication badge in accordance with our design;

FIG. 5 is a bottom view of the communication badge in accordance with our design;

FIG. 6 is a first side view of the communication badge in accordance with our design;

FIG. 7 is a second side view of the communication badge in accordance with our design; and,

FIG. 8 is a rear view of the communication badge in accordance with our design.

In the second design, the broken lines depict portions of the communication badge that form no part of the claimed design.

1 Claim, 6 Drawing Sheets
